UNITED STATES PATENT OFFICE.

CHARLES B. TUTTLE, OF DETROIT, MICHIGAN, ASSIGNOR TO TUTTLE & CLARK, OF DETROIT, MICHIGAN, A CORPORATION OF MICHIGAN.

TOE-WEIGHT FOR HORSES.

1,064,031.

Specification of Letters Patent. Patented June 10, 1913.

Application filed September 1, 1911. Serial No. 647,228.

To all whom it may concern:

Be it known that I, CHARLES B. TUTTLE, a citizen of the United States of America, residing at Detroit, in the county of Wayne 5 and State of Michigan, have invented certain new and useful Improvements in Toe-Weights for Horses, of which the following is a specification, reference being had therein to the accompanying drawings.

10 The invention relates to toe weights for horses and it is the object of the invention to obtain an inexpensive and effective construction of weight securing means.

To this end the invention consists in the 15 peculiar construction of securing device which is struck-up from a single sheet metal blank, and requires no machining, and further in the peculiar construction and combination therewith of the weight 20 as hereinafter set forth.

In the drawings,—Figure 1 is a perspective view of the weight securing member; Fig. 2 is a rear elevation thereof; Fig. 3 is a longitudinal section through said member 25 as attached to the horse's hoof and showing the weight in engagement therewith; Fig. 4 is a horizontal section on line $x-x$ Fig. 3.

In the present state of the art toe-weights have been secured to horses' hoofs by providing a securing member having a wedge-shaped tongue for engaging a corresponding recess in the weight. The securing member is provided with screw apertures there-through and is attached to the hoof by 30 said screws. With this structure the weight and the securing member must be fitted to each other either by hand or by machining and thus a considerable portion of the cost of manufacture is in the performance of 35 this work. Furthermore, the securing member is itself attached and held in position upon the horse's hoof solely by the screws. With my improvement I avoid the fitting operation by forming the securing 40 member of sheet metal struck-up in dies to an exact form. I also avoid machine work 45 on the weight member by forming the receiving slot or socket therein of circular section which may be trued by a reamer 50 which exactly fits the corresponding tongue 55 on the securing member.

In detail, A is the securing member which is struck up from a sheet metal blank to form the oppositely projecting ears B and 55 B' centrally connected to a tapering portion

C which is of substantially circular section and is partially closed together in the rear. At the upper end of this portion C is an extension D terminating in a hook E which may be used for holding the strap of a boot 60 whenever one is employed. The ear portions B and B' have their margins turned down to form a sharp bead F and each ear is also provided with an aperture G for a screw and having a marginal turned-down 65 bead H similar to the bead F. The member thus formed may be secured to the horse's hoof by screws I engaging the apertures G and when these screws are tightened the beads F and H will be forced into 70 the hoof, cutting channels therein and forming additional securing devices for preventing displacement. Furthermore the bead F serves the additional function of 75 reinforcing the outer edges of the ears.

The securing member A formed as described is adapted to engage a weight member J which may be of any suitable construction but is provided with a tapering socket K for receiving the portion C. This 80 socket may be initially formed with a core and may then be quickly fashioned by reaming to fit the securing member.

In use, the member A is permanently secured to the hoof, while the weight member 85 J may be detached and replaced at pleasure. By reason of the fact that the portion C is formed from sheet metal and is hollow, it will be slightly yielding and consequently 90 the jarring produced by the striking of the hoof will only have the effect of engaging the weight more securely. On the other hand, when it is desired to remove the weight, this may be done by the exertion of 95 small force.

An important feature of my improvement is that the securing members being formed by dies are always of exact size and will therefore upon interchanging fit the toe weights. The advantage of this is that 100 where a weight is lost it may be replaced by another which is certain to fit the securing member. Furthermore, a series of weights varying in size, can be interchangeably used with a single securing member. 105

The formation of the securing members with inwardly extending sharpened edges or projections greatly increases the security of the weight and relieves the strain from the screws. 110

What I claim as my invention is:

1. The combination with a toe-weight, of a securing device therefor comprising a struck-up sheet metal blank having a tapering shank portion, ears projecting from opposite sides thereof, and turned-in edges for embedding in the hoof, said edges serving as securing means and to reinforce the outer edges of the ears.
- 10 2. The combination with a toe-weight and a securing member therefor comprising a struck-up sheet metal blank having a hollow tapering shank portion, and oppositely projecting ears with turned-in sharpened 15 marginal flanges for embedding in the hoof, said marginal flanges serving as securing means and to reinforce the outer edges of the ears.
- 20 3. The combination with a toe-weight, of a securing member therefor comprising a struck-up sheet metal blank having a hollow tapering shank portion, oppositely extending ears with in-turned marginal flanges, and screw apertures having in-turned marginal portions, said marginal flanges serving to relieve the stress from the securing screws and to reinforce the outer edges of the ears.
- 25 4. The combination with a toe weight, of a securing device comprising a struck up sheet metal blank having a hollow tapering

shank portion longitudinally split whereby said portion is resilient, said toe weight having a correspondingly tapering recess having a frictional engagement with the resilient shank.

5. The combination of a toe-weight provided with a tapering recess of circular section, and a securing member therefor comprising a struck-up sheet metal blank having a correspondingly tapering hollow resilient shank portion of circular cross section for engaging said tapering recess, oppositely extending ears with in-turned marginal flanges, and screw apertures having in-turned marginal portions for the purpose described.

6. The combination with a toe-weight, of a securing device struck up from sheet metal, comprising a hollow tapering shank longitudinally split, and ears extending laterally from the opposite sides of the split portion of the shank adapted to receive securing means, said toe-weight being provided with a bearing having a frictional engagement with the resilient shank.

In testimony whereof I affix my signature in presence of two witnesses.

CHARLES B. TUTTLE.
